KNURLING MACHINE

Lionel R. Jensen, Rockford, Ill., assignor to Geo.
D. Roper Corporation, Rockford, Ill., a cor-
poration of Illinois

Application August 23, 1943, Serial No. 499,613

19 Claims.

(Cl. 80—5.1)

This invention relates to a new and improved knurling machine, and more particularly one designed and especially adapted for knurling the grooved butt portion of a projectile, to prepare the same for application of the copper rifling band that is usually swaged in place therein.

One of the principal objects of my invention is to provide a machine in which every work-piece is given the same definite number of impressions evenly spaced circumferentially of the piece, the knurling roll having only that number of projecting knurling projections thereon, the rest of the periphery being smooth and of slightly reduced diameter. In that way there is avoided any possibility of the knurling on a piece overlapping at one point.

Another object of my invention is to provide a machine in which the work-pieces to be knurled are fed through a curved groove concentric with the knurling roll, and a stop projection is provided in the entrance portion of the groove to serve as a feeler that will enter the groove in each work-piece as it is fed through the groove, whereby to prevent damage to the knurling roll in the event a work-piece has no groove, or the groove is not properly located or of the proper width.

Still another object is to provide a machine of the kind mentioned in which the work-piece is held yieldingly in the entrance portion of the groove, while in contact with the smooth peripheral portion of the knurling roll, until the toothed knurling portion comes in contact with the piece, so as to feed the piece through the groove in the operation of the knurling roll as it rolls the knurl therein.

Still another object is to provide in a machine of the kind mentioned a swingable gate member adjacent the entrance portion of the groove, which is adapted to swing open to admit a work-piece to the starting zone but positively prevent passage of the work-piece to the knurling roll until the smooth portion of the roll is positioned for engagement with the work-piece, said gate being spring actuated to move the work-piece forwardly to the starting point under spring pressure and keep it under spring pressure in contact with the smooth portion of the knurling roll until the toothed portion of the roll takes hold at the commencement of the knurling operation, the swinging movement of this gate being timed by a cam that turns with the knurling roll.

The invention is illustrated in the accompanying drawings, in which—

Fig. 1 is a plan view of a machine made in accordance with my invention;

Fig. 2 is a similar view but showing the parts in moved positions, and

Fig. 3 is a vertical section on the broken line 3—3 of Fig. 1.

The same reference numerals are applied to corresponding parts in these views.

The reference numeral 5 is used to designate the work-pieces, which, as previously indicated, are shot having grooved butt portions 6, the annular ridges 7 in which require knurling, so that when a copper rifling band is swaged in place in these grooves the bands will be gripped securely by these knurled portions and cannot possibly turn with respect to the shot. A knurling roll 8 has a toothed peripheral portion 9 and a smooth peripheral portion 10, the teeth in the portion 9 being exactly the number required for the knurling of the shot in one pass, so that there will be no problem of registration of an end tooth on the roll with an impression in the groove on the shot, and, consequently, no danger of spoiling one or more impressions by a second imprint of one or more teeth on the roll. In other words, at the end of the knurling operation, the smooth portion 10 on the roll comes into position adjacent the finished shot and the shot is then ready to be removed. The smooth portion 10, as clearly appears in Figs. 1 and 2, is on an arc of the same radius with the root portions of the teeth 9, so that the roll 11 is free to turn with respect to the shot when the shot is in the starting position, shown at the left in Fig. 1, in contact with the smooth portion 10 of the roll. The cam 11, which turns with the roll 8, times the entry of each shot to the starting position in relation to the turning of the roll 8, so that each shot will first come in contact with the smooth portion 10 of the roll. The roll 8 thereafter knurls the shot with a rolling action, thereby positively advancing the shot through the machine. In the knurling operation, the shot rolls on the arcuate surface 12 of the top plate 13, the surface 12 being struck on an arc with the vertical shaft 14, on which the roll 8 and cam 11 are mounted for rotation, as a center. A serpentine groove 15, forming a guide-way for the work-pieces 5, is defined between the plate 13 and a companion top plate 16, as clearly appears in Figs. 1 and 2, the shot being entered at one end 17 and after being rolled in the middle arcuate portion 18 leaving the machine on the other end 19. A serpentine-shaped shim plate 20 is mounted with the top plates 13 and

16 on the frame 21 of the machine for slidable support of the flat butt portions 22 of the shot, so that the groove 6 in each properly grooved shot is at the right elevation with respect to the knurling roll 8. A feeler plug 23 mounted in the top plate 13 in the entrance portion 17 of the groove 15 fits closely in the groove 6 when a properly grooved shot is moved past the same, from the position on the left hand shown in Fig. 2 to the position on the left hand shown in Fig. 1. In that way if the operator attempts to pass a shot through the machine which may have no groove in it at all, or may have the groove at the wrong location, such a shot will be stopped by the plug 23 and damage to the machine will accordingly be prevented. When the shot to be knurled has passed the plug 23, it is held releasably, as shown at the left in Fig. 1, between the smooth portion 10 of the knurling roll 8 and a pair of spaced spring pressed plungers 24 and 25 mounted in a box 26 fixed to the top of the plate 13 adjacent the entrance portion 17 of the groove 15. The plungers 24 and 25 have coiled compression springs 27, which normally hold these plungers in a position projecting inwardly a small distance from the arcuate surface 12 toward the knurling roll, as shown in Fig. 2. However, the plunger 24 is easily depressed when the shot is moved into position in abutment with the smooth portion 10 of the knurling roll, as shown in Fig. 1, the shot being then fairly securely held against accidental displacement by its three point engagement, one of which points is on the surface 10, and the other two points at the plungers 24 and 25. However, as soon as the toothed portion 9 of the knurling roll comes into contact with the shot at the start of the knurling operation, the shot is fed positively through the machine in the manner indicated by the right hand shot in Fig. 2. Finally, after the knurling operation has been completed, another spring pressed plunger 28, similar to the plungers 24 and 25 and mounted with its coiled compression spring in a box 29 on the plate 13 adjacent the exit end 19 of the groove 15, serves to hold the finished shot against accidental displacement inwardly from the exit end of the groove, in the manner indicated by the right hand shot in Fig. 1. It will be observed that according to my invention precision in the shape and formation of the ultimate indentures is attained by providing the roll 11 with exactly the number of indenturing teeth to completely indent the periphery of a work-piece portion of predetermined diameter without marring or damaging the previously formed indentures by overrunning or overlapping. Thus when the last of the indenturing teeth has fully engaged in the shot the indenturing is completed. As the roll 8 rotates the smooth portion 10 comes opposite the spring pressed plunger 28. The pressure against the shot being relieved, the plunger is free to move the shot to the position shown in full lines at the right in Fig. 1 with the indentured portion of the shot clear of the indenturing teeth.

The swingable gate member 30 serves, as indicated in Fig. 2, to prevent entry of a shot while another shot is being knurled. It also serves, as shown in Fig. 1, to move a shot under spring pressure from the entrance end of the groove 15 to the starting position, shown at the left in Fig. 1, and to keep the shot spring pressed toward engagement with the smooth portion 10 of the knurling roll, so that the toothed portion 9 will be certain of taking hold on the shot at the commencement of the knurling operation, after

which the shot, as previously stated, is fed positively through the machine by the knurling roll itself. The gate member 30 is pivoted on the top plate 16 at 31 and is normally urged to turn in a counterclockwise direction by a coiled tension spring 32, that is attached at one end on the gate member at 33 and is affixed at its other end on a post 34 projecting upwardly from the top plate 16. A follower roller 35 is mounted on the gate member 30 and runs on the periphery of the cam 11. The spring 32 keeps the gate member spring pressed toward engagement with the cam and so long as the dwell portion 36 on the cam is in engagement with the follower roller 35 the gate member 30 is held in the extreme retracted position, shown in Fig. 2, in which a stop projection 37 on the gate member projects into the groove 15 at a point in front of the knurling roll to positively stop a shot and prevent it from being moved into contact with the knurling roll while another shot is being knurled, as clearly appears in Fig. 2. However, when the roller 35 encounters the drop off portion 38 of the cam, the gate member 30 swings inwardly under action of the spring 32 and moves the shot with it to the starting position, shown at the left in Fig. 1, a roller 39 mounted on the free end of the gate member 30 being arranged to have rolling contact with the shot in this operation. The rise 40 on the cam is in such lagging relationship to the toothed portion 9 of the knurling roll, as appears in Fig. 1, that the shot is kept under spring pressure toward the knurling roll by the gate member 30 until the toothed portion of the knurling roll has taken hold and the knurling operation is definitely under way, after which the gate member 30 is positively moved again back to the retracted position by the cam 11.

In the hollow base 41 of the machine, a worm gear 42 is keyed on the lower end of the shaft 14 and has a worm 43 meshing therewith. The worm is mounted on a shaft 44 which projects from the base and has a drive pulley 45 mounted on the outer end thereof for belt and pulley driving connection with an electric motor, not shown.

The operation of this machine is believed to be apparent from the foregoing description, and although the invention has been described as applied specifically to knurling, it should be understood that it may be applied to other metal rolling operations regardless of the particular type of indenturing operation that may be required. It goes without saying that the invention is not limited to use on shot, but is applicable generally to the knurling, or otherwise indenturing, of any cylindrical or round work-pieces.

It is believed the foregoing description conveys a good understanding of the objects and advantages of my invention. The appended claims have been drawn to cover all legitimate modifications and adaptations.

I claim:

1. In a machine of the character described, a fixed member having a smooth arcuate surface, a rotary member mounted for rotation about a vertical axis substantially coincident with the center of said arcuate surface and having a portion of the periphery thereof smooth and on an arc substantially concentric with the arcuate surface, the balance of the periphery of said rotary member being toothed but also struck on an arc concentric with the aforesaid arcuate surface, means for rotating said rotary member to roll an article between the arcuate surface and the rotary mem-

ber in engagement with the toothed portion of the periphery thereof, a gate member pivoted on a substantially vertical axis for oscillatory movement relative to the feed-in side of the rotary member to move an article into position between the end portion of the arcuate surface and the rotary member, spring means normally tending to swing the gate member in one direction, whereby the article to be rolled between the arcuate surface and the toothed peripheral portion of the rotary member is adapted to be fed in under spring pressure, and means for positively swinging the gate member in the opposite direction in timed relation with the turning of the rotary member so that the article to be operated upon is first engaged with the smooth peripheral portion of the rotary member.

2. A machine as set forth in claim 1, wherein the smooth portion of the periphery of the rotary member is on an arc of substantially the same radius as the root portions of the teeth of the toothed portion of the rotary member, the circumferential dimension of the toothed portion being substantially equivalent to the circumferential dimension of a cylindrical article to be indentured.

3. A machine as set forth in claim 1, wherein the gate member has a stop projection thereon, which in the positively retracted position of the gate member is so disposed with respect to the end portion of the arcuate surface and the feed-in side of the rotary member to prevent entrance of an article to be rolled to the starting position between the end portion of the arcuate surface and the rotary member.

4. A machine as set forth in claim 1, including yieldable detent means on the fixed member projecting inwardly toward the rotary member at one end of the arcuate surface to retain an article in the starting position in contact with the smooth peripheral portion of the rotary member until the article is engaged by the toothed peripheral portion of said rotary member.

5. A machine as set forth in claim 1, including yieldable detent means on the fixed member projecting inwardly toward the rotary member at one end of the arcuate surface to retain an article in the starting position in contact with the smooth peripheral portion of the rotary member until the article is engaged by the toothed peripheral portion of said rotary member, and other yieldable detent means on the fixed member projecting inwardly toward the rotary member at the other end of the arcuate surface to prevent return movement of an indentured article after it has been rolled between the arcuate surface and the toothed peripheral portion of the rotary member.

6. In a machine of the character described, a fixed member having a smooth arcuate surface, a rotary member mounted for rotation about an axis substantially coincident with the center of said arcuate surface and having a portion of the periphery thereof smooth and on an arc substantially concentric with the arcuate surface, the balance of the periphery of said rotary member being toothed but also struck on an arc concentric with the aforesaid arcuate surface, means for rotating said rotary member to roll an article between the arcuate surface and the rotary member in engagement with the toothed portion of the periphery thereof, a gate member pivoted on an axis substantially parallel to the axis of the rotary member for oscillatory movement relative to the feed-in side of the rotary member to move an article into position between the end portion

of the arcuate surface and the rotary member, and means for oscillating the gate member in timed relation with the turning of the rotary member so that an article to be rolled is moved into the starting position by the gate member and engaged with the smooth peripheral portion of the rotary member.

7. A machine as set forth in claim 6, wherein the gate member has a stop projection thereon, which in the retracted position of the gate member is so disposed with respect to the end portion of the arcuate surface and the feed-in side of the rotary member to prevent entrance of an article to be rolled to the starting position between the end portion of the arcuate surface and the rotary member.

8. A machine as set forth in claim 7, including yieldable detent means on the fixed member projecting inwardly toward the rotary member at one end of the arcuate surface to retain an article in the starting position in contact with the smooth peripheral portion of the rotary member until the article is engaged by the toothed peripheral portion of said rotary member.

9. A machine as set forth in claim 7, including yieldable detent means on the fixed member projecting inwardly toward the rotary member at one end of the arcuate surface to retain an article in the starting position in contact with the smooth peripheral portion of the rotary member until the article is engaged by the toothed peripheral portion of said rotary member, and other yieldable detent means on the fixed member projecting inwardly toward the rotary member at the other end of the arcuate surface to prevent return movement of an indentured article after it has been rolled between the arcuate surface and the toothed peripheral portion of the rotary member.

10. In a machine of the character described, a fixed member having a smooth arcuate surface, a rotary member mounted for rotation about an axis substantially coincident with the center of said arcuate surface and having a portion of the periphery thereof smooth and on an arc substantially concentric with the arcuate surface, the balance of the periphery of said rotary member being toothed but also struck on an arc concentric with the aforesaid arcuate surface, means for rotating said rotary member to roll an article between the arcuate surface and the rotary member in engagement with the toothed portion of the periphery thereof, a gate member pivoted on an axis substantially parallel to the axis of the rotary member for oscillatory movement relative to the feed-in side of the rotary member to move an article into position between the end portion of the arcuate surface and the rotary member, a cam turning with the rotary member in concentric relation therewith, a follower on the gate member in contact with said cam, whereby said gate member is arranged to be moved positively in one direction in timed relation to the turning of the rotary member, and spring means for moving the gate member in the opposite direction.

11. A machine as set forth in claim 10, wherein the gate member has a stop projection thereon, which in the retracted position of the gate member is so disposed with respect to the end portion of the arcuate surface and the feed-in side of the rotary member to prevent entrance of an article to be rolled to the starting position between the end portion of the arcuate surface and the rotary member.

12. A machine as set forth in claim 10, including yieldable detent means on the fixed member projecting inwardly toward the rotary member at one end of the arcuate surface to retain an article in the starting position in contact with the smooth peripheral portion of the rotary member until the article is engaged by the toothed peripheral portion of said rotary member.

13. A machine as set forth in claim 10, including yieldable detent means on the fixed member projecting inwardly toward the rotary member at one end of the arcuate surface to retain an article in the starting position in contact with the smooth peripheral portion of the rotary member until the article is engaged by the toothed peripheral portion of said rotary member, and other yieldable detent means on the fixed member projecting inwardly toward the rotary member at the other end of the arcuate surface to prevent return movement of an indentured article after it has been rolled between the arcuate surface and the toothed peripheral portion of the rotary member.

14. In a machine of the character described, a fixed member having a smooth arcuate surface, a rotary member mounted for rotation about an axis substantially coincident with the center of said arcuate surface and having a portion of the periphery thereof smooth and on an arc substantially concentric with the arcuate surface, the balance of the periphery of said rotary member being toothed but also struck on an arc concentric with the aforesaid arcuate surface, the circumferential dimension of the toothed portion being substantially equivalent to the circumferential dimension of a cylindrical article to be indentured by rolling contact with said toothed surface, and means for rotating said rotary member to roll an article between the arcuate surface and the rotary member in engagement with the toothed portion of the periphery thereof, the smooth portion of the periphery of the rotary member being on an arc of substantially the same radius as the root portions of the teeth of the toothed portion of the rotary member, the machine including yieldable detent means on the fixed member projecting inwardly toward the rotary member at one end of the arcuate surface to retain an article in the starting position in contact with the smooth peripheral portion of the rotary member until the article is engaged by the toothed peripheral portion of said rotary member.

15. In a machine of the character described, a fixed member having a smooth arcuate surface, a rotary member mounted for rotation about an axis substantially coincident with the center of said arcuate surface and having a portion of the periphery thereof smooth and on an arc substantially concentric with the arcuate surface, the balance of the periphery of said rotary member being toothed but also struck on an arc concentric with the aforesaid arcuate surface, the circumferential dimension of the toothed portion being substantially equivalent to the circumferential dimension of a cylindrical article to be indentured by rolling contact with said toothed surface, means for rotating said rotary member to roll an article between the arcuate surface and the rotary member in engagement with the toothed portion of the periphery thereof, the smooth portion of the periphery of the rotary member being on an arc of substantially the same radius as the root portions of the teeth of the toothed portion of the rotary member, the machine including yieldable detent means on the fixed member projecting in-

wardly toward the rotary member at one end of the arcuate surface to retain an article in the starting position in contact with the smooth peripheral portion of the rotary member until the article is engaged by the toothed peripheral portion of said rotary member, and other yieldable detent means on the fixed member projecting inwardly toward the rotary member at the other end of the arcuate surface to prevent return movement of an indentured article after it has been rolled between the arcuate surface and the toothed peripheral portion of the rotary member.

16. In a machine of the character described, a fixed member having a smooth arcuate surface, a rotary member mounted for rotation about an axis substantially coincident with the center of said arcuate surface and having a portion of the periphery thereof smooth and on an arc substantially concentric with the arcuate surface, the balance of the periphery of said rotary member being toothed but also struck on an arc concentric with the aforesaid arcuate surface, the circumferential dimension of the toothed portion being substantially equivalent to the circumferential dimension of a cylindrical article to be indentured by rolling contact with said toothed surface, means for rotating said rotary member to roll an article between the arcuate surface and the rotary member in engagement with the toothed portion of the periphery thereof, the smooth portion of the periphery of the rotary member being on an arc of substantially the same radius as the root portions of the teeth of the toothed portion of the rotary member, the machine including yieldable detent means on the fixed member projecting inwardly toward the rotary member at one end of the arcuate surface to retain an article in the starting position in contact with the smooth peripheral portion of the rotary member until the article is engaged by the toothed peripheral portion of said rotary member, and spring actuated feed-in means for applying spring pressure on an article toward engagement between the detent means and the smooth peripheral portion of the rotary member.

17. In a machine of the character described, a fixed member having a smooth arcuate surface, a rotary member mounted for rotation about an axis substantially coincident with the center of said arcuate surface and having a portion of the periphery thereof smooth and on an arc substantially concentric with the arcuate surface, the balance of the periphery of said rotary member being toothed but also struck on an arc concentric with the aforesaid arcuate surface, the circumferential dimension of the toothed portion being substantially equivalent to the circumferential dimension of a cylindrical article to be indentured by rolling contact with said toothed surface, means for rotating said rotary member to roll an article between the arcuate surface and the rotary member in engagement with the toothed portion of the periphery thereof, the smooth portion of the periphery of the rotary member being on an arc of substantially the same radius as the root portions of the teeth of the toothed portion of the rotary member, and spring actuated feed-in means for applying spring pressure on an article to be rolled between the arcuate surface and the toothed peripheral portion of the rotary member to maintain the article in engagement with the smooth peripheral portion of the rotary member until it is engaged by the toothed peripheral portion.

18. In a machine for making indentures, a ro-

tary indenturing roll and a work-piece supporting element associated therewith, the roll having a toothed peripheral portion and a smooth peripheral portion intermediate the ends of the toothed portion, the toothed portion having exactly the number of indenturing teeth to completely indenture the periphery of a cylindrical work-piece without overlapping a finished tooth indenture, a serpentine guide-way for guiding the work-piece in its approach to the indenturing roll and for guiding the work-piece in an arcuate path concentric with the roll center during the indenturing operation and for further guiding the work-piece away from said roll after completion of said indenturing operation, and a gate member acting in coaction with the indenturing roll to prevent said advancement of a work-piece to the indenturing roll until the preceding work-piece has been discharged and the smooth portion of the roll has been positioned to receive said new work-piece.

19. In a machine for making indentures, a rotary indenturing roll and a work-piece supporting element associated therewith, the roll having a toothed peripheral portion and a smooth pe-

ripheral portion intermediate the ends of the toothed portion, the toothed portion having exactly the number of indenturing teeth to completely indenture the periphery of a cylindrical work-piece without overlapping a finished tooth indenture, a serpentine guide-way for guiding the work-piece in its approach to the indenturing roll and for guiding the work-piece in an arcuate path concentric with the roll center during the indenturing operation and for further guiding the work-piece away from said roll after completion of said indenturing operation, a gate member acting in coaction with the indenturing roll to prevent said advancement of a work-piece to the indenturing roll until the preceding work-piece has been discharged and the smooth portion of the roll has been positioned to receive said new work-piece, and means for causing said gate member to urge said new work-piece into engagement with said smooth portion and thereby locating the work-piece in position to be engaged by the indenturing teeth upon rotation of the indenturing roll.

LIONEL R. JENSEN.
